THERMAL CIRCUIT CLOSER

Filed Jan. 4, 1926

Inventor
F. Bosshart

By Clarence A. O'Brien

Attorney

UNITED STATES PATENT OFFICE.

FREDRICK BOSSHART, OF OSNABROCK, NORTH DAKOTA.

THERMAL CIRCUIT CLOSER.

Application filed January 4, 1926. Serial No. 79,123.

The present invention relates to a fire alarm and aims to provide a device which may be placed in a room for actuating a switch upon the occurrence of a fire in the 5 room so as to close a circuit including some suitable alarm such as an electric bell located wherever desired.

A very important object of the invention is to provide an improved circuit closer actuator which comprises a cylinder having a piston slidably therein actuated by cartridges or the like mounted in the cylinder.

Another important object of the invention is to provide an explosive operated circuit closer actuator of this nature which embodies a structure wherein the movement of the parts thereof will be automatically set so as to prevent the actuator from doing the circuit closer any harm.

20 A still further very important object of the invention is the provision of a device of this nature which is exceedingly simple in its construction, compact and convenient, strong and durable, and otherwise well 25 adapted to the purpose for which it is designed.

With the above and numerous other objects in view as will appear as the description proceeds, the invention resides in certain 30 novel features of construction, and in the combination and arrangement of parts as will be hereinafter more fully described and claimed.

In the drawing:—

35 Figure 1 is a sectional elevation of the device embodying the features of my invention, and

Fig. 2 is an enlarged detail sectional view showing the cartridge shells.

40 Referring to the drawing in detail, it will be seen that 5 designates a circuit including a source of electrical energy 6, a knife switch 7, and an audible alarm 8 such as an electric bell. My improved actuator is disposed so 45 that when placed in operation, it will close the switch 7.

Referring particularly to this improved actuator, it will be seen that 9 denotes a closed cylinder preferably having a detachable head 10 at one end. A rod 11 is slid- 50 able through an opening 12 provided in the other end of the cylinder. A piston 13 is mounted on the inner end of the rod 11 and is normally located intermediate the ends of the cylinders. A vent opening 14 is pro- 55 vided in the cylinder 9 off center thereof.

A plurality of cartridge shells 15 are threaded into the cylinder and are provided at their outer ends with reduced necks 16. Cartridges 17 are located in the shells and 60 have fuses 18 projecting therefrom through the necks 16.

The outer end of the rod 11 is reduced as at 19 and a coiled spring 20 is partially wound thereabout, and has its extremity fixed to the 65 reduced portion 19 by means of a screw 21 or any other suitable fastening element. A buffer member 22 is fixed on the other end of the spring 20. This spring 20 has sufficient strength to hold the buffer element 22 in substantial alinement with the reduced portion 19. The buffer member 22 is located in close proximity to the movable parts of the knife switch 7.

The parts are located in a room or the like 75 and should a fire take place in said room, one or more of the cartridges 17 will soon be exploded because of the easy inflammability of the fuses 18, which, if desired, may be led about the room in a network or the like. An 80 explosion of one or more of the cartridges, of course, will cause an expansion of the air in the cylinder 9 behind the piston 13, thereby driving this piston forwardly so as to abut the buffer member 22 against the knife 85 switch 7 to close said knife switch 7, thereby closing the circuit 5 for sounding the audible alarm 8. The spring 20 compensates for the excessive stroke of the rod 11 and piston 13 occasioned by the explosion, thereby preventing any harm being done the knife 90 switch 7.

The piston 13 will travel freely since the air in front thereof may escape through the vent 14, but as soon as the piston passes by 95 this vent, air will be compressed in the forward end of the cylinder, thereby acting as a check to stop the piston 13 and preventing it from doing any harm to the actuator or to the circuit closer with which it may be associated.

It is thought that the construction, advantages, and operation of this invention will now be clearly understood by those skilled in this art without a more detailed description 105 thereof. The present embodiment of the invention has been disclosed in detail, merely by way of example, since in actual practice, it attains the features of advantage enumerated as desirable in the statement of the invention and the above description.

It will be apparent that changes in the de-

tails of construction, and in the combination and arrangement of parts may be resorted to without departing from the spirit or scope of the invention as hereinafter claimed or 5 sacrificing any of its advantages.

Having thus described my invention, what I claim as new is:—

1. A circuit closer actuator including an explosively operated member, a coil spring 10 partially disposed about one end of the member and fixed thereto, and a buffer element mounted on the free extremity of the coil

spring, said spring being the sole supporting means for the buffer element.

2. A circuit closer actuator including a 15 cylinder, an explosively operated element mounted in the cylinder, cupped shells piercing openings in the cylinder, and provided with reduced necks at their outer ends through which fuses of cartridges mounted 20 in the shells may extend.

In testimony whereof I affix my signature.

FREDRICH BOSSHART.
